US00D929233S

(12) United States Design Patent (10) Patent No.: US D929,233 S
(45) Date of Patent: * Aug. 31, 2021

(54) COSMETIC CONTAINER

(71) Applicant: AMG Co., Ltd., Tokyo (JP)

(72) Inventor: Hiroki Hasegawa, Tokyo (JP)

(73) Assignee: AMG CO., LTD., Tokyo (JP)

() Term: 15 Years

(21) Appl. No.: 29/724,358

(22) Filed: Feb. 14, 2020

(30) Foreign Application Priority Data

Nov. 19, 2019 (JP) 2019-025663

(51) LOC (13) Cl. 09-01

(52) U.S. Cl.

USPC D9/504; D28/7

(58) Field of Classification Search

USPC D9/500-505, 519, 521, 529, 537,

D9/544-546, 549, 550, 556, 573-575,
